(57) **CLAIM**

The ornamental design for a draining rack system, as shown and described.

DESCRIPTION

FIG. 1 is a front-top-right perspective view of a draining rack system, showing my new design;

FIG. 2 is a rear-bottom-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is an enlarged view of the area 9 of FIG. 1; and,

FIG. 10 is an enlarged view of the area 10 of FIG. 2.

The broken line circles in FIGS. 1, 2, 9, and 10 depict the limits of the enlarged view and form no part of the claimed design.
